UNITED STATES PATENT OFFICE

JOHN OVERMEYER, OF NEW YORK, N. Y., ASSIGNOR TO WILLIAM WILLHEIM CO., INC.,
OF NEW YORK, N. Y.

DESIGN FOR A TEXTILE FABRIC OR SIMILAR ARTICLE

Application filed December 9, 1932. Serial No. 46,398. Term of patent 3½ years.

To all whom it may concern:

Be it known that I, JOHN OVERMEYER, a citizen of the United States of America, residing at 555 West 151 Street, New York, New York, have invented a new, original, and ornamental Design for a Textile Fabric or Similar Article, of which the following is a specification, reference being had to the accompanying drawing, forming a part thereof.

The figure is a plan view of a textile fabric showing the complete width of my new design except for the portion between the break lines which is similar to that on either side thereof.

I claim:

The ornamental design for a textile fabric or similar article as shown and described.

In testimony whereof I have signed this specification.

JOHN OVERMEYER.
